ICE-BOXES

Joaquin Gil Vidales and Enrique Gil Vidales, both of
130 San Federico St., Barcelona, Spain

Filed Aug. 17, 1956, Ser. No. 604,721

Claims priority, application Spain May 21, 1956

1 Claim. (Cl. 312—305)

The present invention relates to improvements in the manufacture of ice-boxes or refrigerators and more specifically in such facilities as are used in households.

It is well known that the use of conventional ice-boxes always has been subject to difficulties. Several suggestions have been made in this connection although there have been encountered always some drawbacks of practical importance, such as the need of momentarily withdrawing from the ice-box the articles or receptacles located near the door when it is necessary to reach some items placed behind these articles.

The main object of the present invention is to avoid these drawbacks by providing an improved construction for the supports of the articles to be stored, by means of which it is possible to place within the reach of the hand all of the contents of the cabinet while obviating the formation of dead spaces of any substantial volume.

A further object of the invention is to provide a new system of construction for ice-boxes which results in the hygienic advantage that there is no need of either disturbing or piling up the foods owing to the difficulty in placing them at the rear portion of the cabinet.

According to the invention, the improvements consist in arranging the stepped supports for holding the trays on a revolving assembly associated with the door of the cabinet in such a manner that upon revolving it communicates successively all of the trays or supports in front of said door.

Within this feature, the system can be modified by several embodiments generally depending on the nature and type of construction of the cabinet itself. For example, when dealing with ice-boxes, the container for the ice bar or piece can be arranged over the revolving assembly itself or separate therefrom and such embodiments will be reflected in the specific construction of the supports in the upper part of the revolving members. In automatic refrigerators, the evaporator will be likewise mounted separately from the revolving ensemble.

Other and further objects and advantages of the invention will be evident from the following description taken together with the accompanying drawings, in which:

Fig. 1 is a diagrammatical elevation, partially in section, of an embodiment;

Fig. 2 is a section on the line 2—2 of the Fig. 1;

Fig. 3 is a section on the line 3—3 of Fig. 1;

Figs. 4, 5 and 6 are structural details, schematical, of supports for trays which can be used in the system;

Fig. 7 is a structural detail of another embodiment;

Fig. 8 is a plan view of Fig. 7;

Fig. 9 is a further embodiment of securing means for the tray, and

Fig. 10 is a plan view of Fig. 9.

In connection with Figures 1 to 3 there is disclosed the assembly intended for ice-boxes. Numeral 10 is the bottom of the cabinet, provided with the corresponding thermal insulation 11. A hole 12 has been formed in the central area of the bottom 10 and crosses the latter

2

vertically, thus communicating the inner space 13 of the cabinet with a lower cavity 14 for the purposes which will hereinafter be described.

A bearing member 16 is secured on the upper face of the bottom 10 by means of screws 15, said bearing member being in coaxial relation with the hole 12, and it is vertically drilled in correspondence with said hole 12. A tubular shaft 17 is arranged in the described holes and is secured to the ring 18 rotatably mounted on the bearing 16, so that the ring and shaft can revolve about the bearing.

The shaft 17 extends upwardly to the upper portion of the cabinet, where it abuts a dish which communicates with the interior of said shaft and is adapted to receive an ice block 20 to cool the cabinet.

The water resulting from the melting of the ice is collected on the dish 19 and flows down the interior of the shaft 17 until leaving through lower end 21 slightly protrudes within the space 14 where it can be recovered by any conventional means.

The shaft 17 has secured thereto a plurality of frames 22 formed of horizontal sections secured to the shaft by one end thereof and connected with one another by means of vertically extending members or parts 23. The upper part of the frames 22 is provided with a tubular drum or rim 24 which can roll in contact with the rollers 25 adapted to revolve in the roller supports 26 which are secured to the lateral walls of the cabinet at the locations which can best be seen in Fig. 2. Furthermore, pillars 27 have been provided which extend upwardly to support the edges of the ice dish which, in this manner, should not be entirely supported by the shaft 17. Between the frames and the dish there is formed a space which can be used to store the articles to be maintained at a lower temperature.

The pillars or members 23 have squared supports 28 which protrude laterally with respect to the longitudinal axis of the respective members, and has its concavity directed towards the center of the system, as seen in Figs. 4 and 5.

The shaft 17 is formed with ribs or shoulders 29 located at the same level as the horizontal legs 30 of the supports or right-angle members 28 and faced with the spaces comprised between any two adjacent pillars. A triangular or sector shaped tray 31 can be placed on one of the supports of two adjacent pillars and over the shoulder of the shaft 17 which faces the space defined between those pillars. Thus, the tray may receive the articles to be stored. The vertical oscillation of these trays is prevented by the upper stops 32 spaced apart from the corresponding ribs or shoulders in an amount corresponding to the height of the tray and are formed with an incline or bevel 33 to facilitate the insertion of the latter. The horizontal displacement of the trays over the supports is prevented by the vertical leg portions 34 of the right-angle members 28.

By suitably distributing these sets of supports along the height of the system, the relative positions of several trays can be combined so that the necessary space is formed between two successive trays in order to just provide room enough for the article or object placed on the lower tray. The arrangement of the trays between several other trays is shown in Fig. 3.

When, owing to constructive or like requirements, it is necessary to mount the container or ice dish nonrotatably, the construction disclosed in Fig. 7 can be used.

The dish 19 is supported by the transversely extending rods 35 connected by the ends thereof to the right-angle rod supports 350 which are secured to the lateral walls of the cabinet by means of the screws 351. The opposite ends of said rods 35 are connected, for example, by welding them to the bearing 36 which is in alignment

with the bearing 16, previously described, so that the shaft 17 can be guided between both bearings as in the previous case. For the purpose of giving further stability to the dish 19, in this latter case the rods 35 have welded thereto, at intermediate locations, the ends of two auxiliary rods 352 extending to the rear wall of the cabinet and secured thereto by means of a combination of rod supports and screws similar to that described, and are numbered with the same reference numerals. In this embodiment the drain of the dish is effected through the short tube 37 leading into the shaft 17.

In this latter embodiment, the assembly of the ice dish can be changed to an evaporator or the like device adapted to take heat.

At all events it will be understood that the assembly is placed within the refrigerator or ice-box so that the door of the latter is located between two supports 26, and by suitably revolving the assembly all of the departments can be reached without unloading any articles or receptacles.

As is apparent from Figs. 9 and 10, the revolving assembly may be also simplified by reducing it to the tube 17, and by securing the trays directly thereupon. The shaft 17 is provided with pairs of radial holes 38 and a slot 39 the width of which is less than the diameter of the holes and directed downwardly. The frames 22 are dispensed with and the trays are supported by the brackets 40 which is equivalent to that of the previously described trays, but they are provided at a portion adjacent the tube 17 with an extension 41 which is directed downwardly and from which two radial tenons 42 project adapted to be received in respective slots 39. These tenons have respective heads 43 of greater diameter than the width of the slots but less than the holes 38 so that the support can be placed in position by radially inserting the tenons through the holes and then displacing the support downwardly until fitting the tenons in the slots.

As will be understood, each said support is so built that it comprises the means just necessary to support a tray like those described, or else the support and the tray may be formed as a single part, such as is illustrated in Figs. 9 and 10.

Of course, the trays can be provided with the usual devices for facilitating the arrangement of the objects, for example, holes for placing bottles or eggs. Also, several modifications such as shape and size can be used with the present invention without departing from the scope thereof as defined in the appended claim.

We claim:

In a refrigerator cabinet having at least a bottom, and two side walls, a fixed refrigerant supporting member adjacent the upper end of the cabinet, a first journal centrally positioned in said refrigerant supporting member, a second journal centrally positioned in said bottom and open at its lower end, aligned with said first journal, a vertical tubular shaft mounted for rotation in said journals, a tube extending through said refrigerant supporting member and communicating with the interior of said tubular shaft to provide a drain from said refrigerant supporting member through the open lower end of said second journal, a pair of vertical rectangular frames disposed at substantially right angles to each other secured at the mid points of their top and bottom horizontal members to points adjacent the top and bottom, respectively, of said shaft for rotation with said shaft, a plurality of unequidistantly spaced pairs of circular supporting collars secured to said shaft, the underside of the top collar of each pair being downwardly and inwardly beveled, elongated L-shaped supporting members carried by each vertical member of each frame, each L-shaped member having a horizontal leg forming a shelf projecting inwardly in alignment with the lower collar of each pair of collars, and a plurality of substantially triangular trays, each having its apex supported horizontally on a lower collar of a pair of collars, the bevel of said upper collars facilitating insertion and removal thereof, the opposite base corner of each tray seating on the horizontal shelf of an L-shaped member, the length of each shelf being sufficient to support adjacent corners of two trays.
